UNITED STATES PATENT OFFICE.

FERDINAND DRLICA, OF DETROIT, MICHIGAN, ASSIGNOR OF ONE-HALF TO FRANK BEST, OF DETROIT, MICHIGAN.

AUTOMOBILE-HOOD.

1,304,751.

Specification of Letters Patent. Patented May 27, 1919.

Application filed April 26, 1918. Serial No. 231,033.

To all whom it may concern:

Be it known that I, FERDINAND DRLICA, a citizen of the United States, residing at Detroit, in the county of Wayne and State 5 of Michigan, have invented a new and useful Improvement in Automobile-Hoods, of which the following is a specification.

This invention relates to automobile hoods and has for its object a hood provided with 10 a concealed hinge at its top where the two leaves hinge together. It has been customary heretofore to use at this place an exposed hinge. The concealed hinge or watershed hinge that has been used at the sides 15 of the hood has been an impossible construction for use at the top of the hood for it will not open out in the proper direction and if used at all at the top would have to have its parts exposed instead of being under 20 the hood, which is necessary to make it concealed.

My improved form of hinge may also be used at the side with a slight modification, for the hinge is capable of opening up in 25 either direction when the elements are designed with this end in view.

In the drawings,—

Figure 1 is a perspective of the hood showing the hinges in place.

30 Fig. 2 is a section on the line 2—2 of Fig. 1.

Fig. 3 is a section on the line 3—3 of Fig. 1.

Fig. 4 is a fragment of either the cowl 35 or radiator seat for the hood.

The hood is made up of the usual two leaves of two sections which hinge at the top and with the sections hinged together at the sides. Where the leaves are hinged 40 together at the top the hinge must open outward and prevent opening inward, while at the sides where the two sections hinge together the hinge must open inward and avoid opening outward. The so-called 45 water-shed hinge of the Wright Patent #829,498 is in quite general use but this hinge only opens one way and it can only be made to open one way, namely, with the sections folding toward the side where the 50 hinge parts are located and away from the concealed side. Obviously this hinge can, therefore, be used to little advantage on the top of the hood as the parts could not

be concealed. It is, therefore, customary to use this common piano type hinge. 55

My hinge is a strictly concealed hinge and usable either at the top or side with a slight modification. It comprises a pair of pintles *a*, *a* connected at each end by a yoke *b*. The stock forming the leaf is folded 60 upon itself for some distance and then formed into an eye *c* of just slightly less length than the hood. This forms what I term an inset eye, for it is inset from the edge of the leaf. The tops of the yoke arms 65 form abutments preventing the hinge opening inward. The ends of the pintles *a*, *a* protrude at both ends of the hood and may be seated in the grooves *d*, *d* in the cowl or radiator ledge. The yoke *b* is formed so 70 that its inner surfaces diverge from top to bottom to allow the leaves to swing by the vertical position so that they will hold themselves up. The folded edges of the leaves almost meet when the leaves are in the usual 75 position for service. It will, therefore, be apparent that the hinge is a completely concealed one.

The same general principle is adopted in the hinge shown in Fig. 3, which is the 80 side hinge. The pintles *e*, *e* are connected by a bar *f*. This bar has its side abutting against the upper section so that the upper section does not hinge with respect to the bar. At the lower end the bar is given an 85 arcuate shape and the lower section of the leaf turns upon the pintle and around the arcuate surface. The upper pintle is considerably inset while the lower pintle is inset just beyond the edge of the lower section. Both upper and lower sections are 90 folded so as to present abutments *g* which help prevent the hinge opening outward and tend to establish a water seal. A stiffening lug *h* may be used inside of the folded 95 portion. This lug is integral with the bar *f*.

Screws *y* hold the pintles *c* in the yoke *b* and allow the removal of a pintle when it is desirable to separate one leaf *f* from the other. 100

What I claim is:

1. A hood, having a pair of leaves hinged together blindly at the top and each having an inset and concealed eye, and a pair of pintles one passing through each eye and 105 adapted to seat on the cowl and on the ra-

diator, and a connector for rigidly connecting the two pintles.

2. In a hood, a pair of sections each provided with a concealed and inset eye, a pair 5 of pintles one passing through each of said eyes, and a connecting member for holding said pintles in a permanent relative posi-

tion so that the sections are always held together as a unit and are removable from their seats as a unit.

10

In witness whereof I have hereunto set my hand on the 20th day of April, 1918.

FERDINAND DRLICA.
